CLAIM

I claim the ornamental design for a cosmetic brush, as shown and described.

DESCRIPTION

FIG. 1 shows a front isometric view of a cosmetic brush according to the present design.

FIG. 2 shows a rear isometric view of the cosmetic brush of FIG. 1.

FIG. 3 shows a left side elevation view of the cosmetic brush of FIG. 1.

FIG. 4 shows a right side elevation view of the cosmetic brush of FIG. 1.

FIG. 5 shows a top view of the cosmetic brush of FIG. 1.

FIG. 6 shows a bottom view of the cosmetic brush of FIG. 1.

FIG. 7 shows a front view of the cosmetic brush of FIG. 1.

FIG. 8 shows a rear view of the cosmetic brush of FIG. 1.

FIG. 9 is another top view thereof; showing the cosmetic brush in a second configuration in an environment; and,

FIG. 10 is another top view thereof; showing the brush portion in another configuration.

In FIGS. 1, 2, 3, 4 and 7 the broken lines are for the purpose of illustrating portions of the cosmetic brush that form no part of the claimed design. In FIG. 9 the broken lines are for the purpose of illustrating environment only that form no part of the claimed design.

1 Claim, 9 Drawing Sheets
